UNITED STATES PATENT OFFICE.

FRANK F. PARKER, OF GARDNER, MASSACHUSETTS.

DESIGN FOR A CHAIR.

SPECIFICATION forming part of Design No. 15,670, dated December 30, 1884.

Application filed October 13, 1884. Term of patent 3½ years.

To all whom it may concern:

Be it known that I, FRANK F. PARKER, a citizen of the United States, residing at Gardner, county of Worcester, and State of Massachusetts, have invented and produced a new and original Design for a Chair, of which the following is a specification, reference being had to the accompanying photographic print, forming a part thereof.

10 My design relates particularly to the backs of chairs, and has for its object to give to the chair-back a beautiful and symmetrical appearance.

15 The figure shows in perspective a chair the back of which embodies my new and original design.

20 My novel design for a chair consists in a top panel for the back, the said top panel having a convexed upper edge, a concaved lower edge, and an intermediate strip or band cut through to form what is known as "fret-work," and present a series of openings.

The upper strip, *a*, having a convexed up-

per edge, the lower strip, *b*, having the concaved lower edge, and the intermediate strip, *c*, of what is known as "fret-work," constitute the top panel and represent my design. I ornament such convexed top edge of the panel with notches or corrugations or indentations after any suitable design or pattern. 30

I claim —

The design for a chair herein shown and described, the same consisting of the upper panel for the back, the upper part, *a*, of the panel presenting a convexed edge, the lower part, *b*, presenting a concaved edge, the central part, *c*, presenting the appearance of fret-work and containing openings, as shown.

In testimony whereof I have signed my name to this specification in the presence of two subscribing witnesses.

FRANK F. PARKER.
